UNITED STATES PATENT OFFICE.

ROBERT LOWE SHANNON, OF CHICAGO, ILLINOIS.

KEY-ACTUATED ROPE LOCK.

Application filed March 31, 1924. Serial No. 703,195.

My invention relates to improvements in key actuated rope locks, and consists in the combinations, constructions, and arrangements herein described and claimed.

5 An object of my invention is to provide a key actuated rope lock which is adapted to receive the two strands of a rope which closes the open end of a mail bag or other like retainer and to permit the strings to be pulled through the lock in one direction so as to close the bag but at the same time to prevent the strings from being moved in the opposite direction to open the bag.

10 A further object of my invention is to provide a device of the type described in which it is necessary to employ a key to open the lock in order to permit the strings to be moved so as to open the bag.

15 A further object of my invention is to provide a device of the type described in which a partition is used for keeping the two strands separate as they pass through the lock, whereby the strands are prevented from becoming twisted while in the lock.

20 A further object of my invention is to provide a device of the type described in which a part of the rope guiding means for the lock is also used as a combination for the lock, thus permitting various locks to be employed, each lock being actuated by a different key.

25 A further object of my invention is to provide a device of the type described which is provided with a name plate, whereby the device is especially adapted for use with mail sacks or the like.

30 Other objects and advantages will appear in the following specification, and the novel features of the invention will be particularly pointed out in the appended claim.

35 My invention is illustrated in the accompanying drawings, forming part of this application, in which

Figure 1 is a side elevation of the device,

40 Figure 2 is a top plan view of the device, showing a card disposed in place,

Figure 3 is a vertical section through the device,

45 Figure 4 is a section along the line 4—4 of Figure 3,

Figure 5 is a section along the line 5—5 of Figure 3, and

Figure 6 is an end elevation of the device.

50 In carrying out my invention I provide a U-shaped member 1 which carries a card

retaining member 2. The member 2 is adapted to receive a card 3 as clearly shown in Figure 2. The space enclosed by the sides of the U-shaped member 1 is divided into two compartments by means of a partition 4. A strip 5 is disposed around the edges of the member 1 and encloses the working parts of the device.

55 In Figure 3 I have shown the strip 5 as being provided with an opening 6 through which two strands 7 are adapted to pass. The strands are passed beneath a pin 8 that is provided with teeth 9 for a purpose hereinafter described. The strands 7 are then passed over a pair of clamping members 10 and 11. A portion of the strip 5 is bent inwardly into the interior of the device and provides a partition 12 over which the strands are adapted to move. The inner end of the partition 12 is bent at 13 and is provided with notches 14 for a purpose hereinafter described. The partition 4 is provided with an opening 15 which is of the same shape as the opening 16 in one of the walls of the member 1. A key 17 is adapted to be received in the openings 15 and 16 and when turned is adapted to come in contact with both of the members 10 and 11. In Figure 3 I have shown a key in a position to hold the members 10 and 11 so as to permit the strands 7 to be moved in either direction.

60 Before the key can be swung into engagement with the members 10 and 11 it must first pass by the portion 13. The key is provided with projections 18 which are adapted to be received by the notches 14 as the key is moved thereby. If any other key is used, it will strike the portion 13 and will prevent the operator from bringing the key into contact with the members 10 and 11. In this way, a positive means is provided for preventing the members 10 and 11 from being swung into the full line position unless the proper key is used. A groove 19 is also provided in the key 17 and is adapted to receive the partition 4 so as to permit the key to be swung or turned within the casing.

65 The rope clamping members 10 and 11 are provided with grooves 20 which extend from the ends 21 of the members to a short distance below the ends, as clearly shown in Figure 3. A portion of the ends 21 that are not provided with grooves 20 are serrated at 22 and are adapted to bite into the rope.

to hold the latter when the members are shown in the dotted line position shown in Figure 3. Leaf springs 23 tend to swing the members 10 and 11 into the dotted line position.

From the foregoing description of the various parts of the device, the operation thereof may be readily understood. As heretofore stated, the strands 7 are fed 10 through the lock in the manner shown in Figure 3. When the strands are pulled in the direction of the arrow shown in Figure 3, the members 10 and 11 will be swung into the full line position and will permit this 15 movement. If now, however, the strands are pulled in the reverse direction, they will first swing the members 10 and 11 into the dotted line position, whereupon the members will crowd the strands up against the 20 top of the member 1 and also against the teeth 9. The teeth 21 will also engage with the strands. These three points of engagement prevent the strands from being moved in the reverse direction to that shown by the 25 arrow in Figure 3. In case the mail bag to which the device is attached becomes loosened, it is merely necessary to pull the strands 7 in the direction of the arrow, whereupon the bag is again tightly closed.

30 This operation may be performed without the use of a key, since the members 10 and 11 can be moved into the full line position shown in Figure 3. If it is desired, however, to open the bags, it is first necessary to obtain 35 the key which opens the lock.

In opening the device, the key is rotated into the dotted line position shown in Figure 3 and is prevented from further movement by means of a stop pin 24. The members 10 and 11 are provided with recesses 25 which receive the key when the key is swung so as 40 to open the lock. The key is left in the lock when the strands 7 are pulled in the reverse

direction to that shown by the arrow and therefore prevents the members 10 and 11 from swinging into the dotted line position.

45 The device is very compact in structure and may be used in place of the ordinary fastening means for mail sacks. The members 10 and 11 provide a novel and efficient 50 means for gripping the strands so as to prevent the strands from movement in a direction opposite to that shown by the arrow. The device is extremely simple in construction, and is durable and efficient for the 55 purpose intended. A card holder 2 permits the device to be used in the same manner as the standard mail sack lock.

Every mail sack must be provided with a name plate. The lock provides a novel 60 means for securing the name plate to the draw strings of the sack, and at the same time for locking the strings so that the bag cannot be opened. In this way the lock performs a double function.

65 I claim:

A mail bag lock comprising a casing, one wall of said casing having a portion thereof bent inwardly to form a rope guide, spring-pressed clamping members having serrated 70 portions for engaging with the strands of rope, a pin having a serrated portion adapted to cooperate with the serrated portions on said clamping members for preventing the movement of the strands in one direction, 75 said clamping members being positioned in said casing to bind the strands against the wall of the casing and against the serrated portion of said pin, spring means for moving said clamping members toward said pin, and 80 a partition extending between said clamping members for preventing the strands of rope from becoming tangled within the casing.

85 ROBERT LOWE SHANNON.
